UNITED STATES PATENT OFFICE.

JOSEPH S. MCKINLEY, OF CINCINNATI, OHIO, ASSIGNOR OF ONE-HALF TO
EDWARD JOOS, GEORGE W. HANDMAN, AND WILLIAM WEHRMAN, OF
SAME PLACE.

INK-DISTRIBUTER.

SPECIFICATION forming part of Letters Patent No. 678,019, dated July 9, 1901.

Application filed November 30, 1900. Serial No. 38,243. (No model.)

To all whom it may concern:

Be it known that I, JOSEPH S. MCKINLEY, a citizen of the United States, residing at Cincinnati, in the county of Hamilton and State of Ohio, have invented certain new and useful Improvements in Ink-Distributors for Lithographing-Presses, of which the following is a specification.

The object of my invention is to provide a laterally - reciprocating spreading - roll primarily adapted to a lithographic press. In presses of this class it has been found impossible to employ the laterally-moving roll of an ordinary printing-press. In lithographic printing it is essential that the spreading of the ink be very uniform, or else the print will be streaky and spoil the work. It is also absolutely essential that the direction of motion shall not be reversed while the platen and stone are moving either forward or backward. The reversal of the revolution of the laterally-moving spreading-roll must take place at the end of the platen movement. It is also very desirable to readily lift out the spreading-roll during the operation for the purpose of removing foreign substances. It is also desirable to have the spreading-roll free to move upward under the action of the platen and stone. This free upward movement is also desired in the bottom or main inking-rolls.

The features of my invention will be more fully set forth in the description of the accompanying drawings, forming a part of this specification, in which—

Figure 1 is a sectional view showing in diagram the various parts of a lithographic press. Fig. 2 is a top plan view of the inking-rolls. Fig. 3 is a side elevation of Fig. 2. Fig. 4 is an enlarged elevation of one end of the spreading-roll. Fig. 5 is an end elevation of Fig. 4. Fig. 6 is a section on line xx , Fig. 4.

My invention is applied to the ordinary lithographic press or printing - press, and I have shown sufficient parts to illustrate the method of attaching my invention thereto.

A represents the pitman that reciprocates the bed B by means of a stationary rack-bar A^1 , fixed to the bed of the press, and a rack-bar A^2 , fixed to the under side of the platen. A gear A^3 is journaled on the end of the pitman.

shaft engaging said rack-bars. Upon the bed B is placed the lithographic stone.

C represents the inking bed or plate at the left of the stone.

D represents a pair of ordinary ink-feeding rollers delivering ink on the inking-plate C.

E represents a series of ink-spreading rolls for distributing the ink uniformly over the inking-plate.

I have shown two sets or four stone-inking rolls F. Above the set are shown three laterally - moving spreading - rolls G. On the guideway of the platen-carriage is mounted a rack - bar a , its operating position being shown in dotted lines, Fig. 3, inside of the main frame b of the press. The lower rolls are revolved by their contact with the inking-plate and then by their contact with the stone, being free to move up and down.

In order that the spreading-rolls may be positively revolved while they are moving laterally, I provide the following devices: s represents journal-brackets attached to the side frame, in the upper ends of which are half-journals f' , in which the ends of the spreading-rolls journal. As the roll rests by gravity in its said journal, it is free to be raised from position or to yield upwardly to compensate for any inequalities passed between the rolls. Of course various means for carrying out this idea might be employed, such as making the journals whole and the brackets free to rise in guides or other mechanical expedients for making the spreading-rolls float over the inking - rolls free to rise.

c represents gears journaled on a stud-shaft journaled in the said journal-brackets s and meshing with the teeth of rack-bar a . d represents gears feathered to engage with a spline e on the shaft of the laterally-moving spreading - rolls. It will be seen that the spreading-roll and its gear d may be readily raised and dropped back again into position.

In order that these spreading-rolls G may be moved positively in a given lateral direction, and also that they may float and be readily lifted out of contact with the inking-rolls, and also that they may serve as floating-rolls, free to rise and fall, I provide the following instrumentalities: H represents a worm on extended shaft H' of the spreading-rolls G.

At each end of the worm *m* is a boss *h*. This worm is in engagement with a segmental fork or worm-driver *I*, which is sustained by stem *i* upon the supporting-bracket, as shown in Fig. 4. *j* represents a spring coiled upon the stem for cushioning its movements, serving as a follower to preserve the engagement of the worm-driver. The opposite end of said roller *G* is shown with a shaft extension, upon which is splined the driving-gear *d*, through which this shaft slides as it is moved laterally by the worm driving-gear *H I*. It is essential that, as hereinafter explained, the lateral movement of the roll shall terminate at the end of the pitman-stroke and that the reverse motion shall take place in unison therewith. In order that this may be accomplished automatically, I provide the following features: At each end of the worm are shoulders *k*, abrupt at one end and tapering at the other end *l*. The bosses *h* also form an annular shoulder limiting the lateral travel of the spreading-roll in either direction. The worm on the spreading-roll is preferably so proportioned relative to the bed travel that the bed and spreading-roll normally reach the ends of their travel simultaneously. It is evident that any raising of the spreading-roll, stopping its lateral travel, ends this relative proportion, ultimately causing the spreading-roll to reach one end of its travel first. I have invented a compensating mechanism to regulate these parts (bed and spreading-roll) to proper time movements again whenever their relative arrangement is thus disturbed. Thus when the spreading-roll is raised and upon being again engaged reaches its end of travel first it will revolve idly until the bed has reached the end of its travel, when the same mechanism automatically causes the travel of the spreading-roll to be reversed simultaneously with the initial reverse travel of the bed. Thus the relative uniform movements of the bed and spreading-roll are automatically preserved and require no attention from the operator. He may raise the spreading-roll at any time required and drop it at will, knowing that the parts will again automatically assume the proper time movements.

The inking-rollers, being of composition matter, are somewhat soft. The spreading-rolls, being of steel and heavy, weigh upon the inking-rolls. Therefore whenever the press is idle the steel spreading-rollers would frequently press the inking-rollers out of shape. To obviate this, means are provided for lifting the inking-rolls from the stone and the spreading-rolls from the inking-rolls. The inking-rolls and the spreading-rolls are frequently raised in unison—for instance, to remove from the rolls any paper or foreign matter which may accidentally have become attached to the rollers, or, again, to prevent too heavy inking at a given time. The paper operated upon may be thick or thin, or a single piece may vary, and also foreign inequali-

ties are sometimes present. These inequalities are all provided for, the inking-rolls being free to rise from the form, carrying with them the spreading-rolls, or the spreading-rolls being free to rise from the inking-rolls independently. If the relative travel of the bed and spreading-roll laterally has been disturbed, so that the spreading-roll begins one end of its travel while the bed is at a position intermediate of its extreme ends, the pressure of the spreading-rolls on the soft inking-rolls causes a shading. This result is entirely obviated by my invention. The spreading-roll never begins its lateral travel in either direction, except at the initial ends of the bed travel in either direction.

In order to understand the operation of the roll in practice, let it be assumed that the spreading-roll *G* has been raised for some purpose while the bed is still traveling, as frequently happens in practice, causing the roll *G* to reach one end of its lateral travel prior to the time in which the bed has reached one end of its travel. The roll will revolve idly, the cam *k* engaging and riding over the yoke *I* until the bed has reached the end of its travel, and the reverse travel of the bed immediately imparts a reverse lateral movement of the spreading-roll. When the roll *G* has thus reached its end movement before the bed has reached its end movement, the cam *k* in its revolution constantly deflects the yoke *I*. It is obvious that if this driver were not a yielding member, but stationary, the revolution of the roll bringing the cam-shoulder *k* to bear against it would either throw the roll completely out of gear or break the supports. The driver *I* being swiveled also allows it to accommodate itself to the taper of the worm whenever it is engaged as well as when engagement is made from the idle position riding on the cam *k* to the working position in the threads of the worm.

To illustrate the specific manner in which the roll is made to turn idly when reaching the end of its movement before the bed reaches the end of its travel, assume that, looking at Fig. 4, the spreading-roll *G* has reached the end of its travel on which letters *xx* appear before the bed has reached the end of its travel. The continued revolution of the roll *G*, due to the continued movement of the bed in the same direction, will bring the inclined portion *l* of the cam-shoulder *k* (see Fig. 6) into engagement with the worm-driver *I*, and as this cam is brought to bear it depresses the worm-driver *I* until the shoulder *k* has passed over the same, when the driver *I* slightly rises again and again encounters the tapering edge *l* of the cam. Thus as long as the roll is turned in this direction the worm is kept out of engagement; but the minute the bed reaches the end of its movement and starts in a reverse direction the reverse direction of the roll *G* will throw the abrupt shoulder *k* of the cam against the

worm-driver I and move the worm-driver into the threads of the worm for the reverse movement of the spreading-roll G.

It will be observed that the inking-rolls F are shown as driven in a given direction by their contact with the platen and stone. In case the frictional contact of the spreading-roll G with the inking-rolls F should not be sufficient to secure a positive revolution of more than one of the spreading-rolls when a series are employed, the driving-gears are provided. Two of the rolls G, as seen in Fig. 2, are provided with the driving-gears. The central one is driven slightly by its contact with the inking-rolls F. Each one of these spreading rolls G must be free to rise and fall and be readily lifted off of the inking-rolls. To accomplish this, the worm-driver I is of segment form, and the opposite end of the roll may be supported in a half-journal or rest upon the rolls, as desired. By this construction it will be seen that the spreading-roll may be disengaged momentarily and reengaged at any position along the worm and obtain the requisite direction of travel, and if the worm-driver reaches the end of the worm before the direction of the platen is reversed, it continues to revolve without lateral movement until the platen action is reversed, preventing a reversal of lateral movement during the travel of the bed in a given direction. If this should occur, the print would be streaky or not of uniform color, and the reversing during the act of making the impression cause unequal pressure and wear of the lower inking-rolls and frequently obliterate the work or drawing on the stone. The prevention of reversal during the act of printing is exceedingly important, as the printing of different colors has to be performed with great delicacy and niceness.

I believe I am the first to secure positively the reversal of lateral travel of the spreading-rolls at the end of the bed travel only and also allowing the engagement of the worm with the worm-driver at any point of the stone and bed travel.

Having described my invention, I claim—

1. In a device of the class described, in combination with an inking-roll, a spreading-roll journaled above the same, means for rotating said spreading-roll, mechanism adapted to reciprocate said spreading-roll and to yield vertically to inequalities without being disconnected, and means for positively reversing the lateral travel of the spreading-roll at the initial ends of the platen travel, substantially as specified.

2. In a device of the class described, the combination of a traveling bed, an inking-roll driven thereby, a spreading-roll journaled above said inking-roll, means for rotating said spreading-roll, mechanism for laterally reciprocating said spreading-roll, and means at each end of the spreading-roll for automatically connecting and disconnecting said mechanism whereby the travel of the spreading-

roll is reversed simultaneously with the initial reverse travel of the bed, substantially as specified.

3. In a device of the class described, the combination with a traveling bed, of an inking-roll driven thereby, a spreading-roll journaled above the inking-roll, means for positively rotating said roll, vertically-yielding mechanism for laterally reciprocating said spreading-roll, and means for automatically connecting and disconnecting said mechanism whereby the travel of the spreading-roll is reversed simultaneously with the initial reverse travel of the bed, substantially as specified.

4. In a device of the class described, the combination with a traveling bed of an inking-roll driven thereby, a spreading-roll journaled above the inking-roll, means for positively rotating said spreading-roll, mechanism actuated by the spreading-roll for reciprocating said roll laterally, the said mechanism being adapted to yield vertically, and means for automatically connecting and disconnecting said mechanism at the ends of the lateral movements of the spreading-roll, whereby the travel of the spreading-roll is reversed simultaneously with the initial reverse travel of the bed, substantially as specified.

5. In a device of the class described, the combination with a traveling bed of an inking-roll driven thereby, a spreading-roll journaled above said roll, means for rotating said spreading-roll positively, a worm-driver on the frame, a worm formed on the spreading-roll, and means formed on each end of said worm adapted to be engaged by the worm-driver causing the roll to revolve without lateral movement whenever it reaches the end of its travel before the end of the bed travel and to automatically reengage at the end of the bed travel, substantially as specified.

6. In a lithographing-press, in combination with the inking-rolls, a journal attached to the side frame, a vertically-yielding yoke-driver attached to the side frame, a floating spreading-roll, one end of which engages said journal, a worm-shaft formed on said roll adapted to rest upon said yoke worm-driver, and means for positively rotating the said spreading-roll, substantially as specified.

7. In a lithographing-press, in combination with the inking-rolls, a journal attached to the side frame, a spring-controlled worm-driver attached to the side frame, a spreading-roll supported in said journal and adapted to yield vertically, a worm-shaft formed on said spreading-roll resting upon the said worm-driver and adapted to be operated thereby, and means for rotating the said gear positively whereby the spreading-roll is laterally reciprocated and free to rise from its journal-supports and drop back into engagement with the gear and worm connections, substantially as specified.

8. In a lithographing-press, in combination with the inking-rolls, a journal-bracket attached to the side frame, a spreading-roll, one

- end of which rests in the said journal, means for reciprocating the said spreading-roll, the said means being adapted to yield vertically without disconnecting, a rack secured to the 5 journal-bed, a gear journaled on said bracket engaging said rack, and a gear feathered and splined on the spreading-roll shaft engaging the first-named gear, substantially as specified.
10. In a lithographing-press, in combination with the inking-rolls, a floating spreading-roll journaled above the inking-rolls, a worm at one end of the spreading-roll shaft, a spring-controlled worm-driver supported on 15 the side frame upon which the worm of the spreading - roll shaft yieldingly rests, and means for rotating said spreading-roll, substantially as specified.
10. In a lithographing - press, in combination with the inking-rolls, a journal-bracket attached to the side frame, a spring - controlled yoke worm-driver swiveled to the side frame, a spreading-roll, the ends of which engage the said journal - bracket and worm- 25 driver, the said roll being free to rise vertically, a worm on the spreading-roll engaging the worm-driver, a rack on the traveling bed, a gear journaled on the journal-bracket engaging said rack, and a gear feathered and 30 splined on the spreading-roll shaft, and engaging the first-named gear, whereby the said spreading-roll is positively rotated and reciprocated laterally, but is free to rise from its journals and drop back into engagement with 35 said gear and rack connections, substantially as specified.
11. In a device of the class described, the combination with a traveling bed of an inking-roll driven thereby, a spreading-roll journaled 40 above the inking-roll, means for positively rotating said spreading-roll, a worm-driver on the machine-frame, a worm on the spreading-roll, and a cam at each end of the worm adapted to insure the reciprocation of the 45 spreading-roll at the ends of the bed travel, substantially as specified.
12. In a device of the class described, the combination with a bed of an inking-roll driven thereby, a spreading-roll journaled 50 above the inking-roll, means for positively rotating the spreading-roll, a worm on the spreading - roll, a spring - controlled worm- driver adapted to have vertically-yielding engagement and disengagement with said worm, substantially as specified. 55
13. In a device of the class described, the combination with a traveling bed, of an inking-roll driven thereby, a spreading-roll journaled above the inking-roll, means for positively rotating the spreading-roll, a worm on the spreading-roll, a spring-controlled worm- driver swiveled on the machine-frame and adapted to have yielding engagement and disengagement with said spreading-roll, substantially as specified. 60
14. In a device of the class described, the combination of a traveling bed, an inking-roll driven thereby, a spreading-roll journaled above said inking-roll, means for rotating said spreading-roll positively, a worm on the 70 end of said spreading-roll, a spring-controlled worm-driver mounted on the machine-frame adapted to have vertically-yielding engagement and disengagement with said worm, and a cam formed at each end of the worm adapted to arrest the lateral travel of the spreading-roll at intermediate points of the bed travel, and to automatically reengage said reciprocating mechanism at the ends of the bed travel, substantially as specified. 75
15. In a device of the class described, in combination with an inking-roll, a spreading-roll, a worm-driver, a worm on the spreading-roll, a cam at the end of the worm-threads having an inclined shoulder adapted to engage the worm-driver when the roll is traveling toward said end, and an abrupt shoulder adapted to engage the driver when the roll is rotated in the opposite direction to throw the worm-driver and worm-threads into 80 reengagement for the reverse travel of the roll, substantially as specified. 85
